AIR OR GAS BLAST ELECTRIC CIRCUIT BREAKERS

Albert Roxburgh, London, Albert Leigh, Kenton, Harrow, and Jerrold Joseph Fellerman, London, England, assignors to Associated Electrical Industries Limited, London, England, a British company

Filed Mar. 7, 1960, Ser. No. 13,276

Claims priority, application Great Britain Mar. 9, 1959
19 Claims. (Cl. 317—59)

This invention relates to air or gas blast electric circuit breakers.

The term gas as used throughout the preamble of this specification and in the claims appended thereto includes by definition, air.

A gas blast breaker commonly has in each phase a gas receiver and current interrupting contacts, the number of sets of which contacts depends on the voltage at which the breaker is designed to work. The contacts are separated by a gas blast which is admitted from the gas receiver through blast control valves to the interrupter heads carrying the contacts.

According to the present invention a gas blast electric circuit breaker comprises in a phase, a gas receiver, at least two sets of serially connected circuit interrupter contacts in which means are provided for a manually initiated separation of less than the full number of sets of series contacts available for automatic operation of the breaker.

Conveniently, one half of the number of sets of contacts operable on an automatic operation are operable on the manually initiated operation.

Preferably, time delay means are provided whereby after operation of the means provided for the manual operation, the rest of the serially connected contacts are opened simultaneously or in two or more successive stages.

The invention is of application in opening a small value of electric current in a highly inductive circuit, such as a transformer primary circuit whose secondary is on open circuit or is loaded with reactors. By means of the invention the over voltage due to current chopping to zero (i.e. decreasing suddenly to zero) will be limited by restriking across the initially opened contacts whose withstand voltage, i.e. that voltage at which those gaps will restrike will be less than that of the full number of gaps employed for the automatic opening.

The means provided for the manually initiated operation of less than the full number of contacts may conveniently comprise an additional blast valve not operable on automatic operation, or means whereby one of the blast valves operable on automatic operation is initially independently operable on the manual operation either by independent operation of separate parts of an operating shaft or by initial operation of means movable relative to a single operating shaft.

These and other features of the invention are more fully hereinafter set forth in the specification and in the claims appended thereto.

Three embodiments of the invention will now be described with reference to the accompanying drawings in which,

FIG. 1 is a schematic view of part of one embodiment,
FIG. 2 is a side view from the left of FIG. 1 of the rest of the embodiment,

FIG. 3 is a fragmentary schematic view of an alternative embodiment,

FIG. 4 is a complete schematic of still another embodiment; and

FIG. 5 is a schematic view of the top part of the breaker of FIGS. 1-3.

2

In the diagrams fixed and movable pivots are indicated respectively by solid dots and circles.

Referring now to FIGS. 1, 2 and 5, there is illustrated in the normal circuit closed position an embodiment of the invention using a single operating shaft 49 and means for operating one blast control valve 41 independently of the other blast control valve 42.

For the purpose of illustration only, the circuit breaker of FIGS. 1 and 2 is of the seal-off type. Such a breaker is itself well known and avoids the use of a sequential switch additional to the circuit interrupter contacts. This is achieved by the chamber 201, FIG. 5 containing the contacts 202 and 203, FIG. 5 having an exit which after interruption of the circuit is closed so that the pressure gas maintains the separation of the contacts and the circuit isolated. Reclosure of the contacts is provided by dumping the air in the contact chamber to atmosphere.

The control valves 41 and 42 are mounted in the air receiver 40 and are assemblies of generally cylindrical form with pipes 43 and 44 leading to support insulators 205 and 206, FIG. 5 carried by the air receiver 40 and each carrying a double breaker head serially connected in line 207. The blast control valve assembly 41 has entry ports 45 closed by a piston 46. An operating rod 47 for the piston 46 having a flange 47" resting on the piston 46 extends freely through the piston 46 and is pivotally connected at 47' to an arm 48 rigidly carried by the operating shaft 49. The piston 46 prevents entry of air from the air receiver 40 through ports 45 to the pipe 43. The blast control valve assembly 41 also includes a pressure-operable piston 50 biased to the position shown by a coil spring 51 to seal off exit ports 52.

The blast control valve assembly 42 is of substantially the same construction as assembly 41 as so far described, the like parts in assembly 42 being suffixed *a*. The operating rod 47a of assembly 42 is however secured to the piston 46a. The rod 47a is connected via an arm 48a with the operating shaft 49 in the same manner as is the rod 47. The operating shaft 49 is mounted for rotation in bearings, not shown. An arm 53 is rigidly secured to the shaft 49 and pivotally connected at 54 (FIG. 2) to a rod 55 biased to the right hand (in FIG. 2) by an opening spring 56 of coil form operating on an end piece 57 on the rod 55. The arm 53 is held in the position illustrated (FIG. 2) against the bias of the spring 56 by a trip-free linkage.

The linkage comprises a link 58 pivotally connected to arm 53 at 54 and pivotally connected at 59 to a short arm 60 of a bell crank lever 61 which is itself rotatable about a fixed pivot at 62. A longer arm 63 of the bell crank lever 61 is pivotally connected at 64 to a link 65 pivotally connected at 66 to link 67. The links 65 and 67 together act as a collapsible strut preventing bell crank 61 from rotating anti-clockwise from the illustrated position. This is achieved by a link 68 pivotally connected to links 65 and 67 at their pivot 66 and by the pivoted connection of the link 67 at 67' to a latched rod 82 of a closing cylinder 83. The link 68 is pivotally connected at 69 to links 70 and 72. Link 70 is rotatable about a fixed pivot 71 but is prevented from rotating anti-clockwise (in FIG. 2) by pivotal connection of the link 72 at 73 to a lever 74 which is itself pivoted at 75 and carrying a roller at 76. A latch member 77 pivoted at 77' prevents the lever 74 rotating clockwise (in FIG. 2). A trip coil 78 is positioned adjacent the latch 77 and is energisable through leads 80, 81 from a trip supply (not shown). The rod 82 has a flange 84 within the cylinder 83 and a flange 85 outside the cylinder and the rod 82 is held in the illustrated position by means of a latch 86 pivoted at a fixed pivot 87 and acting on the flange 85.

The latch 86 is biased to the left hand (in FIG. 2) by a coil spring 88.

The closing cylinder 83 has a piston 89 fed by entry passage 96 from a servo valve cylinder 95 of the servo valve assembly 95'. The servo valve assembly is of the pressure differential type. Such valves are well known in the switchgear art. The servo valve cylinder contains a piston 97 biased by a coil spring 98 to the left hand (in FIG. 2) to close an entrance 96' to passage 96. An electromagnetically operable pilot valve 99 is biased to the right hand by a spring 100 to close exit port 99'. The pilot valve 99 has an operating coil 101 energisable from a breaker closing electrical supply through leads 101' and 101''. Pressure air is connected to the servo valve cylinder 95 from the air receiver 40 by means of a pipe 102. Pressure air leaks through a restricted passage 97' in the piston 97 and the piston is maintained in the illustrated position by the sum of the forces due to the spring 98 and the pressure behind the piston i.e. on the right hand side (in FIG. 2) acting against air pressure tending to move the piston to the right. Pilot valve 99 prevents the air pressure behind the piston from escaping to atmosphere through 99'. The closing piston 89 closes in the illustrated position an entrance 90 to a pipe 91 leading from the closing cylinder 83 to a pneumatic safety switch 92' comprising piston 93 operable in cylinder 92 and biased to the left (in FIG. 2) by a coil spring 94. The piston 93 carries a bridging contact 93'.

The blast control valve assembly 41 includes a means for operating the piston 46 independently of the rod 47 i.e. independently of piston 46a of the valve assembly 42. The operating shaft 49, arms 48 and 48a, rods 47 and 47a and the trippable linkage 58, 61, 65, 67, 68, 70, 72 and 74 remaining in the illustrated position. The means just referred to comprise a tube 103 fixed to piston 46 and surrounding the rod 47 and the tube is held in the illustrated position (FIGS. 1 and 2) by means of a prop 104 positioned underneath (in the figures) a flange 105 of the tube 103. The prop 104 is pivoted at 106 on the arm 48 and at 108 to a link 107. The link 107 is pivoted at 109 to a long arm 110 of a bell crank lever 111 rotatable about a fixed pivot 112. A shorter arm 113 of the bell crank 111 is pivotally connected at 114 to a rod 115 connected with a piston 116 contained in a cylinder 117 and biased to the right (in FIG. 2) by a coil spring 118. The rod 115 carries a contact 119 bridging contacts 120, 121. The cylinder 117 is connected by means of an air supply pipe 125 with a cylinder 126 of a servo and pilot assembly 126'. The servo valve 126' is of the pressure differential type operating in the same manner as servo valve 95'. The cylinder 126 is connected via pipe 130 with the air receiver 40. A servo piston 127 is biased upwardly (in FIG. 2) to close an entry port 129 of the pipe 125. Leakage air pressure entering through restricted passage 127' in piston 127 is retained behind the piston 127 by an electromagnetically operable pilot valve 132 biased by a spring 133 to close exit port 132'. The pilot valve 132 has an operating coil 135 connected in circuit with contacts 120, 121 and 119 by leads 122 and 123. A restricted pipe 136 leads off the pipe 125 into a cylinder 137 of a pneumatic auxiliary switch 137' which contains a piston 138 biased to the right (in FIG. 2) by a coil spring 139. The piston 138 carries a bridging contact 141 for bridging normally open contacts 142, 143. The latter contacts are connected in circuit with a battery 145 the trip coil 78, normally closed contacts 147, 148 and 149 and normally closed contacts 93', 151, 152 by means of electrical leads 144 and 144', 80, 81, 150', 150 and 146. The contact 147 closed in the illustrated position is movable to open contacts 148, 149 on movement of the bell crank 61 anti-clockwise (in FIG. 2), and the closed contact 93' is movable by the piston 93 to open contacts 151, 152. If a fault occurs, the circuit breaker of FIGS. 1 and 2 is opened automatically by a simultaneous operation of the blast control valves 41 and 42 by

energization of the trip coil 78. The latch 77 is pivoted clockwise (in FIG. 2) by the trip coil 78 to release the lever 74 so that the coil spring 56 can rotate the shaft 49 and lower rods 47 and 47a. Links 104 and 107 retain the relative positions illustrated but are lowered with the arm 48 bell crank 111 is rotated clockwise. The lever 74 is rotated clockwise about its pivot 75 allowing the pivot 69 to be moved by the spring 56 to the right and downwardly (in FIG. 2) under the control of link 70. The pivot 64 and the bell crank lever 61 are moved anti-clockwise (in FIG. 2) about the pivot 62. The flange 85 is initially retained in the illustrated position by the latch 86 so that the included angle between link 65 and 67 decreases and an end 68' of link 68 pushes the latch 86 clockwise about its pivot 87. When the link 68 has moved sufficiently downwardly and to the right (in FIG. 2) the latch 86 clears the flange 85 so that the rod 82 is moved downwardly until the flange 84 is adjacent the closing piston 89. As this occurs that part of the linkage consisting of links 70 and 72 and lever 74 is reset i.e. returned by the link 68 to the illustrated position. The latch 77 is biased to return to the illustrated position by a reset spring (not shown). The link 68 is now in a position such that its pivot 69 is as shown in FIG. 2 but its pivot 66 is lowered so that the link 68 slopes downwardly (in FIG. 2) from 69. The contacts 147 are moved away from contacts 148, 149 by the rotation of the bell crank 61.

The downward pull on the rods 47 and 47a lowers the pistons 46 and 46a (FIG. 1) so that the latter uncover the ports 45 and 45a to admit air pressure to the pipes 43, 44 to separate the available interrupting contacts of the breaker. The pistons 46 and 46a seat on parts 155 and 155a of the valve assemblies 41, 42 so as to close restricted passages 156 and 156a leading to top surfaces of the pressure pistons 50 and 50a. The circuit breaker being of the seal-off type the air pressure now holds the contacts apart and the circuit isolated as has hereinbefore been explained. In order to reclose the circuit breaker the closing coil 101 is energised (automatically in the case of auto-reclosing) to move the pilot valve 99 away from its port 99' to allow air pressure on the right hand side of piston 97 to exhaust to atmosphere so that the air supply from pipe 102 moves the piston 97 to the right (in FIG. 2) against the bias of the spring 98. Movement of the piston 97 to the right allows the pressure air to enter the space under the piston 89 through passage 96 so as to raise piston 89. The flange 84 and rod 82 are moved upwards to the illustrated position and so that the flange 85 is relatched by the latch 86. The reset links 70, 72 hold pivot 69 in the illustrated position so that the links 67 and 65 act as a strut pushing the long arm 63 of the bell crank clockwise to the illustrated position. The links 58 and 55 and arms 53 are returned to the illustrated position and the shaft 49 rotated to raise arms 48 and 48a. Rods 47 and 47a and the pistons 46 and 46a of the blast control valves 41 and 42 are returned to the illustrated positions, the piston 46 being returned by the latch 104 acting on the tube 103 of the pistons 46 and 46a. The return allows the air pressure from the contact chambers and columns of the breaker to lower the pressure operable valves 50 and 50a to open ports 52 and 52a to exhaust pressure in the columns and chambers to atmosphere so that the contacts reclose.

It is to be understood that ports 45 and 45a are reclosed before ports 52 and 52a are opened by valves 50 and 50a.

Attention is directed to U.K. patent application 6978/59 which claims and describes such blast control valves.

If it is desired to manually open a highly inductive circuit i.e. one where only a low value of current flows then in the first instance (as explained hereinbefore) only one blast valve namely 41 is operated. The valve 42 is operated thereafter with a time delay. This is provided for as follows: The trip coil 135 is energised to lift the pilot valve 132 so as to allow air on the under side of the

servo valve piston 127 to escape through port 132' so that the piston 127 is lowered by pressure air from the reservoir entering from the pipe 130. Restriction 127' is narrow so that the pressure does not build up beneath the valve 127. Port 129 leading to the pipe 125 is uncovered and the air pressure enters pipe 125 and moves the piston 116 to the left (in the figure) against the spring 118. This movement of the piston 116 moves contact 119 away from contacts 120 and 121 so as to de-energise the trip coil 135 so that pilot valve 132 closes.

The movement of rod 115 to the left (in FIG. 2) rotates the bell crank lever 111 anti-clockwise about pivot 112 so that the longer arm 110 contacts the flange 105, the anti-clockwise movement of the long arm 110, with arm 48 stationary having previously moved the link 107 and the latch 104 so as to decrease the included angle between them and to collapse the linkage consisting of 104 and 107. The flange 105 is then moved downwardly by the continued downward movement of the arm 110 so that the tube 103 pulls the piston 46 downwardly with respect to the operating rod 47 and on to the surface 155. Pressure air is therefore supplied to open only those contacts controlled by valve 41, those controlled by valve 42 remaining closed. The pressure air in the pipe 125 also enters the cylinder 137 through the restricted pipe 136 and, after the piston 116 has moved to the left, moves the piston 138 to the left (in FIG. 2) against the spring 139 bridging the contacts 142 and 143 with the contact 141. This completes the circuit through normally closed contacts 147, 148 and 149, lead 150, normally closed contacts 151, 152, and 93', leads 150', 81, 80, 144', and 144, to energise the trip coil 78 from battery 145 to unlatch roller 76. This allows the spring 56 to rotate shaft 49 and arms 48 and 48a so as to open the blast control valve 41 and move the rod 47 of blast control valve 41 downwardly so that its flange 47" is on top of the piston 46 in the lowered position thereof. The downward movement of the arm 48 moves the latch 104 and link 107 back to the same relative positions as, but lower than the illustrated ones (in FIG. 2) i.e. to the position the ports 104 and 107 assume after an automatic opening operation as the result of the rotation of shaft 49. At this stage the build up of pressure in servo valve 126' has returned piston 127 to the illustrated position and shut off the pressure air at port 129. The pressure air in the piston 116 has leaked away in a controlled manner say between rod 115 and the cylinder 117.

The circuit breaker will be re-closed in the same way as after an automatic operation, i.e. by providing an air supply to the under side of piston 89. As the shaft 49 rotates, the arms 48a and 48 are rotated in a clockwise direction, the rods 47 and 47a are raised as is the tube 103 by the latch 104 and the bell crank lever 111 and piston 126 are returned to the illustrated positions.

During the closing operation the switch 92' is opened by the pressure air entering pipe 91 to break the energising circuit of the trip coil 78, at 93' before contact 147 remakes so that although the air pressure in the pneumatic auxiliary switch 137' takes some time to leak away and contacts 141, 142, 143 are closed the inadvertent repetition of the second stage of the manual operation is prevented.

Piston 89 returns to the illustrated position by leakage of air say between rod 82 and the cylinder similarly leakage in switch 92' allows the spring 94 to return the piston 93 to the illustrated position to make ready the trip coil energising circuit for partial tripping.

Referring now to FIG. 3 there is illustrated in the normal circuit closed position an alternative embodiment again of the seal-off type of breaker using a single operating shaft 49 but in which the means of FIGS. 1 and 2 for operating one blast control valve 41 independently of the other 42 are replaced by an additional partial trip blast valve indicated generally at 160. Tube 103, latch 104 and the means for operating latch

104 and tube 103 are omitted as well as leads 146, 144. The circuit breaker in FIG. 5 includes blast valves 41 and 42 of the same construction as the blast valve 42 in FIG. 2. The further blast valve 160 comprises a piston 161 in a cylinder 160' biased to the illustrated position by a coil spring 162 so as to seal off entry ports 163 from a pipe 164 leading into the pipe 43. The blast valve 161 is a pressure differential valve, that is to say the air pressure on the top (in FIG. 3) of the piston 161 is balanced by leakage air pressure on the bottom of the piston and by the spring 162. The under side of the piston communicates through a passage 165 with the servo cylinder 166'.

The servo piston 166 is biased to the illustrated position of the spring 16 so as to close the port 165' to atmosphere. The valve 166 is a pressure differential valve maintained in the illustrated position by the leakage pressure behind the valve. An electromagnetically operable pilot valve 168 is biased by a spring 170 to close the exit port 169. The pilot valve has an operating coil 171 in circuit with a pneumatic auxiliary switch 177', contacts 172 and 173 of which are bridged by a contact 174. The bridging contacts 174 are carried by a rod 175 connected to a piston 176 biased to the right (in FIG. 3) by coil spring 176' in a cylinder 177 which cylinder is connected by a pipe 178 with the pipe 164. The rod 175 also carries a bridging contact 179 associated with contacts 180 and 181. The contact 180 is connected by the lead 182 and with the contact 148 of FIG. 3 and contact 181 is connected by lead 183 to battery 145. The shaft 49 carrying the arm 53 partly shown in FIG. 4 is connected with the trip linkage and closing mechanism of FIG. 2. For a manual opening of the breaker energisation of the trip coil 171 moves the pilot valve 167 to the right (in FIG. 3) allowing the pressure behind the piston 166 to leak to atmosphere so that the servo valve 166 moves to the left (in the figure). This allows the leakage air pressure below the piston 161 to leak to atmosphere via pipe 165 and exit port 165'. The pressure air lowers the piston 161 against the coil spring 162 to allow the pressure air to enter via ports 163, the pipe 164 and pipe 43 to operate those contacts of the interrupter associated with control valve 41. The pressure air from pipe 164 enters pipe 178 to move the piston 176 in the cylinder 177 to the left hand (in FIG. 3) to open contacts 172 and 173 to release the pilot valve 168 for reclosure by its spring 170 so that the piston 161 resets to the illustrated position. The movement to the left of the piston 176 (in the figure) closes the contacts 179, 180, 181 so as to energise the trip coil 78 (FIG. 2). This releases the latch 77 to permit the spring 56 to turn the shaft 49, pull down the rods 47 and 47a, lower the piston 46 and 46a to maintain separated the contacts at the top of the column corresponding to pipe 43 and to open the contacts at the top of column corresponding to pipe 43a.

The closing operation is as in the embodiment of FIGS. 1 and 2.

Another embodiment of the circuit breaker is illustrated in the normal closed condition, in FIG. 4.

In the specification of U.K. application No. 3924/56, there is described an air blast breaker, in which the several blast valves in a phase are operable by a torsion shaft or rigidly interconnected half shafts.

In the diagram there is indicated at 200 a cylindrical air receiver which has blast control valves 1 and 2 located within the air receiver and below support insulators (not shown). A pair of half shafts 3 and 4 are mounted alongside the receiver and carry arms 5 and 6 co-operating with pins 5a and 6a which latter are arranged to operate auxiliary valves 1a and 2a to initiate operation of the blast control valves 1 and 2.

The half shafts 3 and 4 carry respective double ended arms 7 and 8 the lower ends of which (in FIG. 4) are biased anti-clockwise by respective coil springs 9 and 10

acting on links 11 and 12. The other ends (i.e. the upper ones in FIG. 4) are connected together through a trippable linkage 13, 14, 15, 16, 17, 18 and latched at 19 (in the illustrated position). A tripping coil 19a is arranged adjacent the latch 19 for releasing the latter.

A lever 20 pivoted at 21 is pivotally connected at 22 to the link 12, at 23 to an operating rod 24 of a piston 25 acting in cylinder 25a communicating through conduit 25b with the low pressure side of control valve 2, and at 26 to a link 27 which is pivotally connected to a bell crank lever 28 latched at 29 (in the illustrated position). A trip coil 30 is arranged adjacent the latch for releasing the latter. An energising circuit of the trip coil 30 includes normally open contacts 30a which are under the control of a piston 31 acting against a spring 31a in a cylinder 32 communicating through conduit 33 with the low pressure side of the control valve 1.

In order to open a small value of current in a highly inductive circuit a switch (not shown) is manually closed to energise the trip coil 19a so as to release the latch 19 to allow the spring 9 to turn half shaft 3 and open the control valve 1 so as to open the current interrupting contacts associated with said control valve. The control valve 2 is not opened at this stage so that the circuit has one half of the breaks which would be present on an automatic opening.

Pressure air which has passed through the control valve 1 and the conduit 33 causes the piston 31 to move against its spring 31a to close the contacts 30a to complete an energising circuit through the trip coil 30 so that the latch 29 is released. The spring 10 turns the half shaft 4 to open the remaining control valve 2 and so opens the remaining current interrupting contacts in the inductive circuit.

The release of spring 10 and the rotation of shaft 4 causes arm 8 to pull upon link 13 of the trip linkage 13, 14, 15, 16, 17, and 18 so that the linkage is relatched at 19.

The opening of the blast valve 2 allows air pressure to pass through conduit 25b to the cylinder 25a so that the piston 25 acts through the rod 24 upon lever 20 so as to compress the spring 10, the spring 9 also being compressed because the arms 7 and 8 move together due to their connection by links 13 and 14 which are prevented from collapsing by the resetting of the trip linkage so that it is latched at 19.

Movement of the lever 20 also resets the trip linkage 27, 28 so that it is relatched at 29 whereby when the blast valve 2 closes and pressure air is cut off from the piston 25, the springs 9 and 10 remain compressed. On automatic operation, the trip coil 30 only is energised and releases the trip linkage 27, 28 so that both the shafts 3 and 4 are rotated by the springs 9 and 10.

The blast valves 1 and 2 are of differential design and are arranged to reclose automatically when the auxiliary or servo valves 1a and 2a return to the sealed position and pressure air builds up on the spring sides of the blast valves. The blast valves open when the arms 5 and 6 push open the servo valves 1a and 2a thus allowing discharge of air pressure to the atmosphere on said side of the valves.

Although a partly electrical link has been shown between blast valve 1 and latch or prop 29 it should be appreciated that air pressure could be used directly to unlatch 29 with the appropriate time delay after control valve 1 has opened.

Whilst these embodiments have been described as air operated they may be operated by any suitable gas.

Whilst in these embodiments half the available contacts are initially operated on the manual operation the invention is not limited in this respect, any number of the available sets of contacts can initially be opened and the remainder be opened in one or more subsequent stages. As many stages as there are sets of contacts may be employed. In one example where four circuit

breaker double-break heads are arranged in series i.e. four pairs of sets of contacts each pair having a separate blast control valve each of which valves may be operated sequentially so that one pair of sets of contacts are opened in each of four successive stages until all eight contacts are opened.

Modification of FIGS. 1 and 2 to provide more stages merely needs further blast valves like 41 and further sets of interruptor contacts supplied by the respective valves. Instead of contacts 141 and 142 being arranged to energise the trip coil 78 they will energise a further partial tripping coil like 135 to operate mechanisms like 126', 137', 117, 111, 107, 104, and 103 for each of the further blast valves. The last stage is operated by the connection of contacts like 142 and 143 to energise coil 73. The last blast control valve will be like blast control valve 42.

What we claim is:

1. A gas blast electric circuit breaker comprising in a phase, at least one gas receiver, at least two sets of serially connected circuit interrupter contacts, at least two blast valves for controlling access of gas from the receiver to the contacts, means for automatically initiating simultaneous opening of all said blast valves in response to a fault thereby to simultaneously open all said contacts, and means for opening less than the full number of blast control valves on a manually initiated operation of the circuit breaker such that the remaining blast control valves at least initially remain closed and at least initially less than the full number of contacts are opened.

2. A gas blast electric circuit breaker as claimed in claim 1, in which time delay means are provided whereby after operation of the means provided for the manual operation, the rest of the serially connected contacts are opened.

3. A gas blast electric circuit breaker as claimed in claim 2, having pneumatically operable means and means for connecting pressure gas from the contact side of an initially operated blast control valve with the pneumatically operable means for initiating the operation of at least one of the remaining available blast control valves in the phase with said time delay.

4. A gas blast electric circuit breaker as claimed in claim 3, having a trip coil energizing circuit for operating the said one of the remaining valves and a switch having contacts arranged on operation of the switch by the pressure gas to complete said energizing circuit for operating said further blast valve.

5. A gas blast electric circuit breaker as claimed in claim 1, having an operating shaft for the blast control valves and operating rods connecting the valves to the shaft, said initially operable valve on manual operation having means arranged to move as one with the rod on automatic operation and on the manually initiated operation to be moved relative to the rod in order to operate the initially operated blast control valve only.

6. A gas blast electric circuit breaker as claimed in claim 5, having a tube surrounding the rod and a latch preventing movement of the tube relative to the rod in the closed position of the blast control valve and means which on the manually initiated operation unlatches the tube and moves it with respect to the rod.

7. A gas blast electric circuit breaker as claimed in claim 6, having a lever and a collapsible linkage connected to the lever whereby movement of the lever with the rod stationary collapses the linkage and moves the tube.

8. In a highly inductive electric circuit having a small value of electric current an electric gas blast circuit breaker as claimed in claim 1, wherein on the manually initiated operation the over voltage due to the sudden reduction to zero value of the current is limited by re-striking across the initially opened contacts.

9. In the highly inductive primary circuit of a transformer whose secondary is loaded with reactors an electric

gas blast circuit breaker as claimed in claim 1, wherein on the manually initiated operation the over voltage due to the sudden reduction to zero value of the current is limited by restriking across the initially opened contacts.

10. A gas blast electric circuit breaker as claimed in claim 1, in which the remaining sets of contacts are arranged to open in more than one stage of at least one set at a time with successive time delays between stages, the means provided for the manually initiated operation are arranged to initiate automatically operation of the next stage of at least one set of contacts with the required time delay by actuating like means as are actuated at the beginning of the manual operation until in the last but one stage energization of a trip coil energizable on automatic operation is initiated to open the last stage of at least one set of contacts.

11. A gas blast electric circuit breaker comprising in a phase, at least one gas receiver, at least two sets of serially connected circuit interrupter contacts, at least one blast valve for controlling access of gas from the receiver to the contacts, means for automatically initiating opening of said blast valve in response to a fault thereby to simultaneously open all said contacts, at least one further blast control valve for controlling gas access from the receiver to less than the full number of contacts and inoperable on response of the circuit breaker to the fault, and means for opening said further blast control valve on a manually initiated operation of the circuit breaker such that the first referred to blast control valve at least initially remains closed so that at least initially less than the full number of contacts are opened.

12. A gas blast electric circuit breaker as claimed in claim 11, having a blast valve operating shaft in at least two separate parts and a trippable linkage mechanism interconnecting said parts and arranged on automatic operation of the breaker so that the parts of the shaft are rotated as one while on the manually initiated operation one only of the parts of the shaft is initially operated, the other part being operated after a time delay.

13. A gas blast electric circuit breaker as claimed in claim 12, in which the linkage includes means arranged to reset the linkage after tripping of the linkage and opening of the remaining valve and a single resetting spring being employed for resetting the parts of the shaft and reclosing the breaker.

14. A gas blast electric circuit breaker as claimed in

claim 13, having a trip coil energizing circuit for operating the said one of the remaining valves and a switch having contacts arranged on operation of the switch by pressure gas to complete said energizing circuit for operating said further blast valve.

15. A gas blast electric circuit breaker as claimed in claim 12, having pneumatically operable means and means for connecting pressure gas from the contact side of an initially operated blast control valve with the pneumatically operable means for initiating the operation of at least one of the remaining available blast control valves in the phase with said time delay.

16. In a highly inductive electric circuit having a small value of electric current an electric gas blast circuit breaker as claimed in claim 11, wherein on the manually initiated operation the over voltage due to the sudden reduction to zero value of the current will be limited by restriking across the initially opened contacts.

17. In the highly inductive primary circuit of a transformer whose secondary is loaded with reactors an electric gas blast circuit breaker as claimed in claim 11, wherein on the manually initiated operation the over voltage due to the sudden reduction to zero value of the current is limited by restriking across the initially opened contacts.

18. A gas blast electric circuit breaker as claimed in claim 11, in which the remaining sets of contacts are arranged to open in more than one stage of at least one set at a time with successive time delays between stages, the means provided for the manually initiated operation are arranged to initiate automatically operation of the next stage of at least one set of contacts with the required time delay by actuating like means as are actuated at the beginning of the manual operation until in the last but one stage energization of a trip coil energizable on automatic operation is initiated to open the last stage of at least one set of contacts.

19. A gas blast electric circuit breaker as claimed in claim 11, in which time delay means are provided for opening the rest of the serially connected contacts after operation of the means provided for the manual operation.
